UNITED STATES PATENT OFFICE.

ALFRED W. BENJAMIN, OF CLEVELAND HEIGHTS VILLAGE, OHIO, ASSIGNOR TO
HENRIETTA C. BENJAMIN, OF CLEVELAND, OHIO.

IRONING MACHINE.

Application filed July 26, 1920. Serial No. 399,012.

This invention relates to the class of laundry machines and more particularly to improvements in ironing machines.

The objects of my invention are to provide means whereby the pressure of the ironing head against the roll may be relieved without stopping the operation of the roll; to provide a clutch connection for the roll operating means to be controlled from the same treadle which is actuated for engagement and disengagement of the ironing head with the roll; to provide an improved means for applying extreme pressure to the ironing head against the roll; to provide hand operated means for locking the ironing head in extreme pressure position; to provide an overhanging roll upon which the work can be placed and from which it can be removed from the end thereof, said roll being practically co-extensive with the length of the rest of the machine; to provide a table extending the length of the roll which can be swung toward and away from the roll.

A full understanding of my preferred form of structure will be had from the following description and the accompanying drawings.

Fig. 1 is an end elevation of my machine; Fig. 2 is a front elevation of the same with part broken away; Fig. 3 is a detail view showing the manner of mounting the roll; Fig. 4 is a detail view of the clutch and the arrangement of the drive shaft in the lubricant trough; Fig. 5 is taken on line 5—5 Fig. 4; Fig. 6 is a view of the latch means for the lever which is operated to lock the treadle in pressure position; and Fig. 7 is a vertical sectional view thereof, taken on line 7—7 Fig. 6.

The table 2 which is supported upon the frame work 1 and 1^a supports the roll 3, the table 4, which extends the full length of the roll, and the ironing head 5, which also extends the full length of the roll and which is adapted to be moved into and out of ironing engagement with the roll through its lever operating mechanism, as will be later explained. Roll 3 is suitably padded for ironing and the ironing head may be heated in any suitable manner.

The bracket 6 which extends upwardly from the table 2 supports the shaft member 7 about which the roll 3 is adapted to rotate. As will be seen from Fig. 3, this shaft support 7 extends into the hollow roll

3 to a point substantially midway of its length. This shaft member 7 is provided with bearing portions 8 and 9, the shaft being somewhat tapered toward the end thereof. The collar portions 10 and 11 formed upon the roll are adapted for rotation upon the bearing portions 8 and 9, a shoulder being provided near the inner end of the shaft, and a collar 12 is secured by a set screw on the extreme end of bearing portion 9. 60 The length of the roll is practically co-extensive with the rest of the device and is free to receive work from the overhanging end thereof. A gear 13 upon one end of the roll 3 meshes with the gear 14 which in turn can be thrown into and out of driving connection with the source of power by means of a clutch connection. The clutch here shown comprises a spring pressed pin 15^a carried by gear 15 to engage in one of 65 the apertures 14^a in the gear 14. Any other suitable type of clutch might be employed. Gears 14 and 15 are mounted upon a stud shaft 16^a which has its support in the bracket 16. This bracket is bolted at the points 70 17 to the main bracket 6 so that the gears and clutch can be removed as a unit. The well known grooved collar 18 is provided upon the other side of the gear 14 and the pins 19 carried by the clutch actuating yoke 20 co-operate with said groove in the well known manner to move the clutch member carried by the gear 14 into and out of engagement with the other clutch member.

The yoke 20 is pivotally mounted at 21 upon the bracket arm 22 depending from table 2 and is actuated by means of the rod 23 which extends through the collar 24.

The lower end of the yoke or lever member 20 is pivotally connected with the collar 95 member 24, and a spring 25 is provided between the collar member 24 and the nuts 26 upon the extreme end of the rod 23. Stop 23^a on rod 23 limits the extent of movement of the rod to the left, as viewed in Fig. 100 2, so that when the rod 23 is moved to the right the spring 25 will be placed under tension and the gear 14 will be moved to the left, whereby the two clutch members will be brought into operative engagement.

The gear 14 is of sufficiently wide tread to be at all times in mesh with the gear 13, but it will be understood that since the gear 14 is loosely mounted upon its shaft support, drive connection through the gears 14 110

and 15 will be established only when the clutch members are in engagement. The other end of the rod 23 is pivotally connected at 27 with one end of the bell crank lever which is pivotally mounted at 28 upon a bracket 29 depending from the main table of the machine. The other end of this bell crank lever has pivotal connection at 30 with a vertically disposed rod 31; the lower end of which is pivotally connected at 31' to the pivotal bearing member 33 near the fulcrum of the treadle, from which it will be seen that upon depressing treadle 32 the clutch will be thrown into operative engagement. The lever and spring connections between the clutch and treadle and the ironing head and treadle are so constructed and arranged that the clutch will be actuated by rather slight downward motion of the rod 31 so that pressure upon the treadle will cause the clutch to be actuated before the ironing head is closed.

The power shaft 35 which has worm gear connection with the gear 15, as will be seen in Figs. 2 and 5, is suitably mounted in bearings 36 and 37 formed in the casting set down in the main table of the machine. This casting is also formed with a trough 39 extending along the under side thereof for the purpose of carrying a lubricant for the drive shaft.

The ironing head 5 is pivotally mounted at the points 40 and 41 upon the upwardly extending arms 42 and 43, which are rockably mounted at 44 and 45 upon the shaft 46 which extends across the main table of the machine and has suitable bearings 47, 48. One of these upwardly extending arms is provided at each end of the ironing head. The pin 49 carried by the rearward projections 50 on the ironing head has loose connection in the slot 51 provided in the upper end of the lever arm 52 which is pivotally mounted at 53 upon the bracket arm 54, the last named bracket arm being suitably mounted upon the main table of the machine. As will be seen from Fig. 1, the lever arm 52 extends under part of the main table of the machine and has pivotal connection at 55 with its operating mechanism which is connected at its lower end with the treadle 32. The clevis member 57 which is pivoted at 55 to the lever arm 52 receives the upper screw threaded end of rod 56 and is provided with a lock nut 57a. The clevis member 58 which is pivotally mounted at 59 upon the treadle 32 receives the lower threaded end of the rod 60, a lock nut 61, being provided also for this connection. The rod 60 is screw threaded at its upper end into the lower end of the barrel member 62, a lock nut 63 being provided at this point. The upper end of the barrel is adapted to move up and down upon the rod 56, a nut 64 limiting

its upward movement thereon. The lower end of the rod 56 is spaced somewhat from the upper end of the rod 60, the lower end of rod 56 having sliding engagement in the lower end of the barrel 62. A spring 65 which surrounds the lower portion of the rod 56 has its lower end formed about a boss upon the nut 66 which is threaded upon rod 56 and has a lock nut 67. Nuts 66 and 67 are provided with recesses 66a, 67a in their sides for application of a spanner wrench. The upper end of this spring 65 surrounds the boss 68 provided within the upper end of the barrel. The tension of this spring can be regulated by adjustment of the nuts 66 and 67.

Thus, it will be seen that upon downward movement of the treadle 32 the barrel 62 will also be given downward movement because of its positive connection with the rod 60, while the upper end of the barrel will move freely down the rod 56 and compress the spring against the nut 66. In this way operative connection is effected between the treadle and the lever 52; in other words, the operation of the lever 52 by means of the treadle 32 is effected through a yielding connection as just described, with the result that final pressure upon the ironing head 5 is exerted with a yielding engagement. The screw threaded connection of the rod 60 with the lever 32 and the lower end of the barrel allow adjustment so as to increase or decrease the length of this part of the lever mechanism, and the same adjustment can be had at the upper end of the rod 56. The spring 69, which is connected at its upper end to the under side of the main support of the machine by means of the hook and eye connections 70 and 71, has pivotal connection at its lower end with the treadle at the point 72 opposite the pivotal connection 33 of the clutch actuating lever with the treadle. The normal tendency of this spring 69 is to raise the treadle 32 and through the connections above described move the ironing head away from the roll; which means that in closing the ironing head it is necessary to overcome the tension of the spring 69 and upon full release of the treadle 32 the ironing head is automatically opened by action of this spring.

A bell crank lever 73 is pivotally mounted at the point 74 upon the supporting frame of the machine, the lower arm of this bell crank lever constituting a locking means for engagement with the upper side of the treadle 32 to hold the treadle in fully depressed position. The lower end of the locking lever is beveled so as to properly engage the upper face of the treadle lever 32. The other arm of the bell crank lever 73 is pivotally connected to the lower end of a link or rod member 75 which is pivot-

ally connected at its upper end with the lever member 76. The lever member 76 is mounted upon one end of a shaft 77 which is mounted in suitable bearings 78 and 79, upon the main table of the machine. The other end of the shaft 77 as will be seen from Fig. 1, has positive connection with the upright hand lever 80. An arm 81 secured to shaft 77 carries a screw bolt 82 the upper end of which is adapted to abut the under side of the table 2 as indicated by dotted lines in Fig. 2. Thus the lever 76 is limited in its movement to the right, as viewed in Fig. 2, and the bolt 82 can be set at different positions and secured by means of lock nut 83. In this way the lock lever 73 will be stopped when it comes to proper position over the treadle 32. A spring 84 surrounds one end portion of the shaft 77 and is compressed between the arm 81 and the adjacent face of the bearing member for the shaft 77. Upon manipulation of lever 80, a pin 85, which is fixed upon the inner face thereof is adapted to snap into and out of recesses 86 in the face of the bearing portion 79 formed on the depending flange of the main table 2. Thus, it will be seen that upon movement of the hand lever 80 the engagement of pin 85 in the recesses 86 under the tension of spring 84 will hold the lever in either position to which it is moved.

The table 4 which extends the full length of the roll is suitably mounted at one end upon a bracket 88 into which there is fixed a pivot pin 89 by means of lock pin 90. The pin 89 is pivotally mounted in a deep recess or well 91 in the complementary bracket 91 which is mounted upon the main table of the machine. By this arrangement the table can be swung in a horizontal plane either toward or away from the roll 3. The other end of the table carries a leg 92, the lower end of which carries a pin 93 which is adapted to drop into the recess 94 provided in the table 2. This means is provided for securing the table 4 in position adjacent to the roll. When it is desired to move the table away from the roll it is simply necessary to raise the pin 93 out of its seat and revolve the table on the axis of the pin 89.

That portion of the main table 2 which extends in front of the table 4, as will clearly appear in Fig. 1, can be used also for piling work thereon. An apron 95 extends from the front edge of the table 2 and is bent up, as will be clearly seen from Fig. 1, so as to receive the materials as they come from between the ironing head and the roll. This apron extends the full length of the machine and allows the ironed materials to be received by this apron and moved to the front part of the table 2.

A buffer in the form of a spring 96 is

provided upon the end of the lever 52, as will be seen from Fig. 1, so as to provide a means for absorbing the jar as this end of the lever moves toward the table 2.

The operation of the structure just described is briefly stated as follows:

Upon first depressing the treadle 32 the clutch for the roll is thrown into operative engagement which starts rotation of the roll. Then upon further depression of treadle 32 the tension of spring 69 is overcome sufficiently to move the head 5 into close relationship with respect to the roll 3, at which point the materials to be ironed may be placed upon the roll. Then further pressure applied to the treadle 32 will cause further compression of the spring 65 contained within the barrel, with the result that extreme pressure will be applied to the ironing head 5. Then, if it is desired to lock the treadle in this position, this may be accomplished by operation of the lever 80 which will cause the vertically disposed arm of the bell crank lever 73 to move into the path of the lever 32 and lock the same against upward movement. Should it be desired to release the extreme pressure of the ironing head without stopping the roll, this may be done by releasing the locking member 73 and by proper control of foot pressure upon the treadle 32, part of the pressure thereon can be relieved, that is to say, the tension upon the spring in the barrel can be relieved by allowing the treadle 32 to rise to a certain extent, but at the same time not allowing the spring 69 to exert its opening influence upon the ironing head 5, and furthermore, without allowing disengagement of the clutch for the roll. This partial releasing of the treadle 32 does not affect the clutch but simply relieves the compression of the spring 65, which compression has been caused by the downward movement of the treadle 32 to the extreme pressure position, as above explained. In other words, the spring 65 allows application and relief of final pressure upon the ironing head without affecting the clutch.

With my particular machine, it is possible to place the materials upon the roll from a point at one end thereof without the interference of any part of the frame work or mechanism. Furthermore, this is accomplished without having the roll extend out beyond the other parts of the machine. Then, too, it is possible with my machine to relieve the extreme pressure of the ironing head so that the materials can be inserted and properly adjusted without the inconvenience of stopping and again starting the roll; and if desired the ironing head can be withdrawn from the roll without disengaging the clutch. Furthermore, by means of the lock for the treadle it is not necessary for the operator to continue to

hold his foot upon the treadle in order to hold the ironing head in extreme pressure position. Another important feature of this invention resides in the table from 5 which the work is fed to the roll and which can be swung to a position adjacent the roll or to another position away therefrom. Other advantages flowing from this invention will be apparent to those who are 10 skilled in the art.

What I claim is:

1. In an ironing machine, the combination of an ironing roll, a frame therefor, means mounted upon said frame for movement 15 about a substantially vertical fixed pivot point into and out of parallel relation with respect to said roll, said means in one position being adjacent to said roll and at a level for feeding work into the machine, and 20 in another position serving as a support for the work.

2. In an ironing machine, the combination of an ironing roll, a frame therefor, a table pivotally mounted at its one end portion upon said frame so as to swing through a horizontal plane, a foot upon the other end portion of said table and a releasable locking connection between said foot and support, whereby the table can be either 30 placed in position near the roll or swung away from the same.

3. In an ironing machine, the combination of a frame, a rigid arm extending outwardly from said frame and provided with 35 bearings at its inner and outer ends, a roll provided with bearing means at one end and another bearing intermediate its ends adapted for cooperation with the bearings on said arm, said roll extending endwise beyond 40 the free end of said arm and being provided

at its inner end with an external driving member.

4. In an ironing machine, the combination of a roll, an operating connection for said roll, an ironing shoe cooperating with 4 said roll, means for closing and applying pressure to said ironing shoe, locking means movable into and out of the path of said last-named means for maintaining the same in set position, operating means therefor, 5 and means for securing said operating means in either lock or release position.

5. In an ironing machine, the combination of a roll, an ironing head cooperating with said roll, means including a treadle 5 for closing and applying pressure to said head, a bell-crank lever with one arm adapted to engage said treadle and lock the same in pressure position, and operator operated means for moving said lever to locking position and for releasing the same.

6. In an ironing machine, the combination of an ironing roll, an ironing shoe co-operating with said roll, pivotally mounted arms having pivotal connection with the 65 ends of said shoe, permitting movement towards and from the roll, lever mechanism for moving said shoe towards and from said roll, and an equalizing connection between said mechanism and said shoe at a point 70 substantially midway of the length of said shoe, whereby upon operation of said lever mechanism said shoe is permitted to assume proper seating engagement with the roll, according to the varying thicknesses of the 75 same piece as well as different pieces of work.

In testimony whereof I affix my signature.

ALFRED W. BENJAMIN.
